UNITED STATES PATENT OFFICE.

GEORGE B. FRALEY, OF PHILADELPHIA, PENNSYLVANIA, ASSIGNOR TO
ELIZABETH S. GALBRAITH, OF PHILADELPHIA, PENNSYLVANIA.

APPARATUS FOR PRODUCING MOTIVE POWER FROM LIQUID GAS.

SPECIFICATION forming part of Letters Patent No. 724,278, dated March 31, 1903.

Application filed December 26, 1900. Serial No. 41,023. (No model.)

To all whom it may concern:

Be it known that I, GEORGE B. FRALEY, a citizen of the United States, residing in the city and county of Philadelphia, State of Pennsylvania, have invented a new and useful Improvement in Apparatus for Producing Motive Power from Liquid Gas, of which the following is a specification.

My invention consists of an improved construction of an apparatus for producing motive power from liquid gas, wherein I employ suitable means to gasify the liquid gas and raise the temperature of the same, so that the liability of freezing is prevented, the gas being transformed, so that it can be safely and economically used in a suitable motor, wherefrom the energy for the motive power is derived.

It further consists of novel details of construction, all as will be hereinafter fully described, and particularly pointed out in the claims.

The figure represents a side elevation, partly in section, of an apparatus for producing motive power from liquid gas embodying my invention, showing especially the regulating device and the means for raising the temperature of the liquid gas employed.

In the drawings, 1 designates a tank for the reception of the liquid gas employed, the outlet-pipe 2 therefrom being controlled by the valve 3, said pipe leading into the casing 4, which forms a hot-water tank. The pipe 2 after entering the hot-water tank takes the form of the coil 5, which I term a "gasifying-coil," which latter after leaving the tank 4 leads by the pipe 6 to the chamber 7 of the regulating device 8, the latter being provided with the heat-retaining jacket 9, whereby the chamber 10 is formed, wherein is located the water-holding coil 11, the upper portion of which leads, by means of the pipe 12, into the upper portion of the hot-water tank 4, while the lower portion of the said coil 11 communicates with the lower portion of said tank by means of the pipe 13.

14 designates the base which supports the chamber and jacket, said base having located therein the heating device 15, which dis-
50 charges into the combustion-chamber 16, while

a portion of the heat enters the chamber 10 through the ports 17.

18 designates a plunger which is adapted to reciprocate in the chamber 7 and is suitably packed by means of the packing 19 and the gland 20.

21 designates weights which are removably supported upon the plunger 18, the latter having the arm 22 projecting therefrom, which is provided with the slot 23, through which 60 passes one end of the lever 24, which latter is fulcrumed at the point 25 and pivotally attached to one end of the link 26, the other end of the latter being pivoted to the lever 27, which is fulcrumed at the point 28. 65

29 designates a link having one end pivotally attached to the lever 27, while the other end of said link is connected to the arm 30, which actuates the valve 31, whereby it will be seen that as the volume in the chamber 7 70 varies the plunger 18 will be raised and lowered, which movements will automatically control the supply of liquid gas to the gasifying-coil 5, which is in communication with the chamber 7. 75

By treating the liquid gas in the manner above described it will be apparent that the great difficulty heretofore experienced in the utilization of the same, which ordinarily has the tendency to freeze when released from 80 pressure or during conversion from a liquid to a gaseous state, is obviated, since by my novel arrangement above described I am enabled to gasify the liquid gas and to raise the temperature of the same to a point which 85 eliminates the freezing difficulty and at the same time reduces the gas into an economical and safe working pressure, as said liquid gas becomes gasified in its passage from the coil 5, its temperature being simultaneously raised, 90 and by passing it to the regulator, as above described, the latter will act as a superheater, and the plunger or piston 18 causes an even pressure to be maintained at all times. The gas having been reduced to proper working 95 temperature is now withdrawn from the chamber 7 by means of the pipe 32, which leads to a suitable motor.

It will be understood that the liquid gas which has been subjected to the treatment 100

in the manner described can be readily utilized in motors of various constructions, and I do not desire to be limited to any particular construction of a motor, and it will 5 also be apparent that the liquid gas can be acted upon in other forms of apparatus than that shown and described herein without departing from the spirit of my invention.

Having thus described my invention, what 10 I claim as new, and desire to secure by Letters Patent, is—

1. In an apparatus for producing motive power from liquid gas, means for raising the temperature of the liquid gas, a regulating 15 device constructed and arranged to serve as a superheater, and means for conducting said gas after its reduction to a safe working pressure to any suitable point.

2. In an apparatus for producing motive 20 power from liquid gas, a regulating device through which said gas passes, said regulator constructed and arranged to serve also as a superheater, means actuated by said regulating device for regulating the flow of said liquid 25 gas, and means for conducting the latter from said pressure-regulator to a suitable point.

3. In an apparatus for producing motive 30 power from liquid gas, a gasifying-coil for enabling the temperature of a liquid gas to be raised, a chamber in which said gasifying-coil is confined, a regulating device constructed to serve also as a superheater, and means operated by said regulating device for regulating the flow of said liquid gas to said gasifying-coil.

4. In an apparatus for producing motive 40 power from liquid gas, a liquid-gas receptacle, a gasifying device connected therewith, a water-tank and means for maintaining a circulation of water therein, and means for automatically controlling the supply of gas from 45 said receptacle, said means being controlled by the volume of gas produced by said circulating means.

5. In an apparatus for producing motive 50 power from liquid gas, means for raising the temperature of the liquid gas, means for regulating the supply of said gas to said temperature-raising means automatically, and means for heating said regulating device.

6. In an apparatus for producing motive power from liquid gas, means for raising the temperature of the liquid gas, means for con-

verting the same to a safe working pressure, 55 said means constituting a regulating device, means embodied in said regulating device for controlling the supply of said liquid gas, a heating-chamber surrounding said regulating device, and heating means for said chamber. 60

7. In an apparatus for producing motive power from liquid gas, a source of supply for the liquid gas, a tank containing a gasifying-coil, a pipe from said source of supply to 65 said coil, a valve in said pipe, connection leading from said tank to a heating device, a plunger contained within said heating device, and a pipe leading from said gasifying-coil to the space below said plunger.

8. In an apparatus for producing motive 70 power from liquid gas, a source of supply for the liquid gas, a tank containing a gasifying-coil, a pipe from said source of supply to 75 said coil, a valve in said pipe, connections leading from said tank to a heating device, a plunger contained within said heating device, and a pipe leading from said gasifying-coil to the space below said plunger, in combination with actuating mechanism common to said plunger and valve.

9. The combination of a tank for liquid gas, a valved outlet-pipe leading therefrom, a hot-water tank, a gasifying-coil located therein, a regulating device into which said coil discharges, a heating device for said regulating 85 device, a jacket surrounding said regulating device, and containing a hot-water coil, connections from said hot-water coil to and from said hot-water tank, a plunger located in said regulator, and connections common to said 90 plunger and valve.

10. In an apparatus for producing motive power from liquid gas, a tank containing a liquid gas, a hot-water tank, a gasifying-coil in said hot-water tank, a valved pipe leading 95 from said gasifying-coil to said gas-tank, a regulating device, into which said coil discharges, a plunger in said regulating device, connections from said plunger to said valve, a hot-air chamber surrounding said regulating device, and a coil located in said hot-air 100 chamber and having connections to and from said hot-water tank.
